Att. 24

UNITED STATES PATENT OFFICE

ANTHONY P. COSTA, OF ATHENS, GEORGIA, ASSIGNOR TO BILT-RITE MANUFACTURING COMPANY, OF ATHENS, GEORGIA, A CORPORATION OF GEORGIA

FOLDING TABLE

Application filed April 1, 1930. Serial No. 440,767.

This invention relates to improvements in folding tables, and more especially to a novel folding card table of the type in which the legs fold into a recess on the under side of the top of the table.

Tables of this type usually have their legs braced by means of folding links, and these links not only loosen and make the table wobbly, but they are liable to catch on to the clothing of users of the table, and to pinch the fingers when the legs are manipulated.

The primary object of this invention is to provide such a table in which the legs are braced by one-piece rigid links which have their upper ends slidably connected to resilient rods, so that the brace will be spring-held in position when the legs are perpendicular to the table top.

Another object is to furnish a table of this type, in which the legs are braced by a simple and inexpensive means, which will have a longer life than the braces heretofore used.

With the foregoing objects outlined and with other objects in view which will appear as the description proceeds, the invention consists in the novel features hereinafter described in detail, illustrated in the accompanying drawing, and more particularly pointed out in the appended claims.

Referring to the drawing,

Fig. 1 is a vertical sectional view of a card table equipped with my improvements, and showing the braces holding the legs perpendicular to the table top.

Fig. 2 is a similar view of a fragment of the table, and showing how the brace bows its resilient retaining rod when the brace is to be secured to its retaining screw.

Fig. 3 is a view similar to Fig. 2, but showing one of the legs and its brace during the folding movement of the leg.

Fig. 4 is a bottom plan view of a portion of the table with the legs folded against the under side of the table top.

In the drawing, 5 indicates a table top which, as is usual, is provided around its edge portions, with depending flange bars 6, so as to form a cavity 7 in the under side of the table. Near the corners of the table,

angular metal brackets 8 are secured to the bars 6 by screws 9 and 10, the latter functioning as pivot pins for the swinging legs 11. A spacing collar 12 is arranged on each of the screws 10 between the leg and the adjacent bar 6.

In accordance with my invention, a rigid brace link 13 is pivotally connected at 14 to each leg, and each of these links has its upper end bent over at an angle to the body of the link, to provide a head 15 having an aperture to receive a spring metal rod 16. The latter, as best shown in Fig. 4, passes loosely through staples 17 that are secured to the inner side of the bar 6, and one end of the rod is pointed and driven into the bar, as shown at 18, for the purpose of anchoring that end of the rod. The other end of the rod, however, is free to slide in its retaining staple to take care of the bowing of the rod, as shown in Fig. 2.

Whenever one of the legs is folded or unfolded, the head 15 of the brace link slides along its corresponding resilient rod 16, and for the purpose of connecting the upper end of the link to one of the side bars, the link has a notch 19 in one of its edges to engage a projection or screw 20, the head of which extends inwardly from one of the bars.

In Fig. 1, the links 13 are shown in the position which they occupy when the legs are supporting the table top, and in such position, the rod 16 bears resiliently upon the head 15, so as to cause the notch 19 to interlock with the screw 20. Now, when the legs are to be folded, the link is pulled downwardly, as shown in Fig. 2, and in this movement, the rod 16 is bowed. Then, when the leg is folded, as shown in Fig. 3, the head 15 slides along the rod 16, until the leg comes into parallel relation with its corresponding bar 6.

From the foregoing it is believed that the construction, operation and advantages of the invention may be readily understood by those skilled in the art, and I am aware that changes may be made in the details disclosed, without departing from the spirit of the invention, as expressed in the claims.

What I claim and desire to secure by Letters Patent is:

1. A folding table including a top, a leg pivotally connected to said top, a resilient guide rod connected to said top, and a rigid link having one of its ends slidably connected to the guide rod, and its other end pivotally connected to said leg, said guide rod functioning to secure the leg in folded position under spring tension.
- 10 2. A folding table including a top, a leg pivotally connected to said top, a resilient guide rod connected to said top, a rigid link having one of its ends slidably connected to the guide rod, and its other end pivotally connected to said leg, a projection carried by the top, and a notch in the link to engage said projection.
- 20 3. A folding table including a top, a leg pivotally connected to said top, a resilient guide rod arranged on the under side of the top, a rigid link having a head at one end slidably engaging said rod, and pivotally connected at its other end to the leg, and means including the resilient guide rod for securing the link in position for securing the leg to the top.
- 30 4. A folding table including a top, a leg having one of its ends pivotally connected to said top, a resilient guide rod secured to the under side of the table, a link having an apertured head through which the guide rod extends, means pivotally connecting the other end of the link to an intermediate portion of the leg, and means including the resilient guide rod for retaining the link in position under spring tension to hold the leg perpendicularly relatively to the top.
- 40 5. A folding table comprising a top, a leg having one of its ends pivotally connected to said top, a guide rod having one of its ends anchored to the top, retaining means with which the other end of the rod is slidably connected to permit the rod to bow, a rigid link having one of its ends slidably connected to said rod, and its other end pivotally connected to the leg, and interlocking means including a headed-stud connecting the link to the top.
- 50 6. A folding table comprising a top having a bar on its under side, a leg having one of its ends pivotally connected to said top, a resilient guide rod having one of its ends anchored to said bar, means slidably connecting the rod to said bar, said rod being arranged substantially parallel to the bar, a rigid link having one of its ends slidably connected to the rod and its other end pivotally connected to the leg, and means for interlocking engagement between the link and said bar.
- 60 7. A folding table comprising a top having depending bars on its under side forming an endless flange, an angular bracket secured to each bar near one end of the latter, legs

pivots connected to said brackets, spacers for maintaining the legs inwardly of said bars, a resilient guide rod mounted on the inner side of each bar, and having one of its ends anchored to its respective bar, and its other end movable relatively to said bar, rigid links having their upper ends slidably connected to the guide rods, and their other ends pivotally connected to the legs, screws projecting inwardly from said bars, and notches on the links to engage said screws.

In testimony whereof I affix my signature.

ANTHONY P. COSTA.
